TRAY ASSEMBLY

Grant W. Cramer, Toledo, Ohio, assignor to Dura
Company, Toledo, Ohio, a corporation of Ohio

Application April 27, 1935, Serial No. 18,565

1 Claim. (Cl. 211—77)

This invention relates to trays or turntables adapted to support articles, such as salt and pepper shakers, disposed in convenient position on pantry shelves, stoves, or other places accessible 5 to the housewife.

An object is to produce a simple and inexpensive tray assembly embodying a turntable so that the latter can be swung to a convenient position for enabling the contents selectively to be removed 10 as occasion demands.

Another object is to provide a turntable tray unit which can be inexpensively made from stampings, which occupies a small amount of space, is so constructed that it will turn readily 15 and which has the new and improved features of construction and arrangement hereinafter described.

The invention is shown by way of illustration in the accompanying drawing, in which:

20 Figure 1 is a top plan view of the tray unit with a portion broken away to show the base and fold-carrying plate; and

Figure 2 is a vertical sectional elevation on the line 2—2 of Figure 1.

25 The illustrated embodiment of the invention comprises a turntable tray made from sheet metal stampings, and includes a base 10 having an annular flanged outer supporting portion 11 and a raised central portion 12. Formed in the outer 30 part of the raised portion 12 is an annular groove 13 providing the lower portion of a ball race. Disposed centrally of the raised portion 12 is an upwardly extending surface 14, which provides a bearing support for a triangularly shaped plate 15 35 having holes 16 at the outer edge portion arranged in annular formation to receive balls 17.

Disposed above the plate 15 is a turntable tray 18, which is considerably larger than the base 10, and is rectangular in shape. Extending upwardly 40 from the sides of the tray 18 are flanges 19 to retain the bottles, jars, or other articles supported on the tray, from being displaced therefrom. The tray 18 is formed of relatively thin gauge metal, and, in order to prevent bending of the tray under 45 the weight of the articles disposed thereon, the same is formed with a series of annular downwardly extending or concavo-convex ribs 20, from which radiate similar ribs 21 to the four corners of the tray. Spaced inwardly from the rib 20 are 50 annular ribs 22 and 23, which extend downwardly similar to the ribs 20 and 21. From the ribs 22 and 23 is an upwardly extending rib 24, which provides at the under side of the turntable an annular ball race and is complementary to the race 55 13 so that a portion of the balls 17 is disposed in

the race formed by the rib 24, and the other portion is in a race formed by the rib 13. It is apparent that the construction is such that it not only strengthens the tray so that it is enabled to carry a greater load, but is also such as to provide 5 a ball-receiving race.

The central portion of the tray 18 is formed with an annular depressed part 25, and extending through openings in the depressed portion 25, the plate 15 and the upwardly extending bearing portion 14 is a rivet 26 which serves, in addition to uniting these parts together, to provide a pivot for the tray and plate 15. The rivet 26 is such that it can be applied by a riveting machine, thereby eliminating manual labor, which heretofore 10 has been necessary in similar constructions. It should be noted that the rivet 26 merely connects these parts together, and does not serve as a spacing means, the balls 17 alone acting as 15 spacers.

An advantage of this construction is that the height of the tray can be kept to an absolute minimum. This is made possible by recessing the base to receive the balls and forming the race in the tray in the manner above described so 20 that the ribs do not extend upwardly above the plane of the tray. It will also be understood that by reinforcing the tray 18 by the arrangement of ribs as above indicated, the metal may be of extremely light gauge, thereby keeping the 25 weight as low as possible, as well as the cost of manufacture.

It is to be understood that changes may be effected in details of construction without departing from the spirit of the invention as defined in the appended claim. 30

What I claim as new and desire to secure by Letters Patent is:

A tray of relatively light gauge sheet metal comprising a base having a raised central flat 40 bearing portion and an outer flanged supporting portion, a depressed annular groove spaced outwardly from said bearing portion to provide a ball-receiving track, a ball plate bearing against said flat bearing portion, said plate being provided with a plurality of equally spaced openings, a ball in each of said openings in said plate having a portion disposed in said depressed raceway, a turntable disposed above said ball plate, said turntable being rectangular in form 45 and having an upwardly extending flange on the outer edge portion of each side, a pair of depressed concentric annular grooves or ribs in said turntable providing therebetween on the underside of the turntable a ball raceway com- 50 55

plemental to said first raceway, a depressed central portion in said turntable normally spaced from said ball plate, a rivet extending through said turntable, ball plate and base plate and having the head thereof disposed in said depressed central portion and being substantially flush with the upper surface of the turntable, a

depressed annular reinforcing rib in said turntable disposed outwardly of said concentric ribs, and depressed ribs formed in said turntable and extending radially from said annular reinforcing rib and terminating adjacent each corner of the turntable. 5

GRANT W. CRAMER.
